UNITED STATES PATENT OFFICE.

WALTON E. TAYLOR, OF ST. JOSEPH, MISSOURI.

WIRE-PLACER.

1,136,183.

Specification of Letters Patent. Patented Apr. 20, 1915.

Application filed June 16, 1913. Serial No. 773,804.

To all whom it may concern:

Be it known that I, WALTON E. TAYLOR, a citizen of the United States, residing at St. Joseph, in the county of Buchanan and State of Missouri, have invented certain new and useful Improvements in Wire-Placers; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to a wire placer, and more particularly to a device for use in placing a fence wire against a post, and holding same in position while the wire is being stapled or otherwise fastened to the post; the principal object of the invention being to provide a device of this character for facilitating the application of fence wires, and particularly the lower wires of a series, which it is usually necessary to push downwardly to the proper position on the post. In accomplishing this object, I have provided improved details of structure, the preferred form of which are illustrated in the accompanying drawings, wherein:—

Figure I is a perspective view of a wire placer, constructed according to my invention. Fig. II is an enlarged view of the jaw end of the device. Fig. III is a sectional view on the line III—III, Fig. II. Fig. IV is a view illustrating the use of the placer. Fig. V is a similar view illustrating the use of the staple puller, with which the device is equipped.

Referring more in detail to the parts:—

The device is preferably constructed of suitable metal, and comprises a body 1 having a slightly enlarged end 2, slit longitudinally to provide the teeth 3, which are preferably beveled or pointed as illustrated, in order to provide the beveled inner edges 4. Each of the teeth 3 is provided near its base with an ear 5, which is undercut to provide the sockets 6 between the projecting ends of the ears and the faces of the teeth for receiving the fence wire, which is to be placed against a post. I also prefer to recess the head slightly at its base as at 7, and to cut

away a part of each of the ears 5 at its inner edge, in order to afford space at each side of the staple slot thus forming a pocket 55 at the base of the slot, so that any slight projection on the post may be received between the ears, and thereby enable the head of the tool to lie closer to the post. I prefer to magnetize the jaws of the tool, in order 60 that they may hold the staples, and thereby leave the user's hands free to handle the tool and drive the staple. On the opposite end of the body of the tool is a pointed tooth 8, which may serve as a staple puller 65 as illustrated in Fig. V, by projecting the point of the tooth into the staple and prying the same from its seat.

In using the tool the ears 5 are placed back of the wire so that the wire lies between the ears and the teeth 3, and may be pushed to the proper position along a post. When the wire is in place, a staple is projected between the teeth 3 and over the wire, and driven into the post until it is anchored 75 sufficiently to hold against the tension of the wire when the tool is removed, and so that it may be driven to its full extent after the removal of the tool. It is apparent that the staple may be placed in the head of the 80 tool before the wire is placed against the post, so that it may be held in the tool between the wire and the base of the slide part, thereby leaving the hands of the user free to hold the tool and drive the staple. 85 and without the necessity of the user handling the staple when the wire is under tension.

Having thus described my invention, what I claim as new therein, and desire to secure 90 by Letters-Patent, is:—

1. A wire placer comprising a body member having a head provided with a longitudinal slot forming side teeth: each of said teeth being cut away at one face to a point 95 adjacent the base of the slot, and back-cut to form sockets and overhanging ears, and said head being recessed at its base and along the inner edges of said ears to form a pocket about the base of the slot, substantially as set forth.

2. A wire placer comprising a head provided with a slot forming side teeth, each of said teeth having a sharpened outer end and

being back-cut adjacent the base of the slot to form sockets and overhanging ears; the ears and the head being back-cut to form a pocket about the base of the slot, for the purpose set forth.

3. A wire placer, having spaced teeth at one end, forming a slot, and an ear on each of said teeth, having a back-cut outer end,

forming a socket, and having back-cut inner faces, substantially as set forth.

In testimony whereof I affix my signature in presence of two witnesses.

WALTON E. TAYLOR.
